UNITED STATES PATENT OFFICE.

FREDERICK BENEDICT MCINTOSH, OF ALEXANDRIA, NEAR SYDNEY, AUSTRALIA, AS
SIGNOR TO HEEL COVERING MACHINES LIMITED, OF SYDNEY, AUSTRALIA, A
COMPANY OF AUSTRALIA.

METHOD OF AND APPARATUS FOR ATTACHING COVERS TO HEELS OF BOOTS AND
SHOES.

Application filed June 1, 1928, Serial No. 282,145, and in Australia August 12, 1927.

This invention relates to a method of and apparatus for attaching covers to heels of boots or shoes, whereby said covers are attachable to such heels more expeditiously 5 and at less cost than by known methods and apparatus.

Said method consists in cutting the material of the cover to required size and shape; treating one surface of the cut cover with adhesive; treating the heel with adhesive; feeding the cut cover with its adhesive treated face upwardly disposed in position on a slotted resilient pad; placing the adhesive treated heel in position in relation to the 15 adhesive treated cover; and finally forcing the said heel and cover through the slotted pad, whereby the cover is made to adhere to the heel in its passage through the slotted pad. Where the cover consists of certain 20 flexible material it may be necessary to stretch the cover before it is attached to the heel.

An embodiment of apparatus in accordance with the invention is illustrated in the 25 accompanying drawings, in which Fig. 1 is a perspective view of the apparatus; Fig. 2 sectional elevation on plane 2-2, Fig. 1; Fig. 3 sectional elevation on line 3-3, Fig. 2; Fig. 4 sectional plan on line 4-4, Fig. 2; Fig. 5 perspective view of resilient pad and 30 holder therefor; Fig. 6 perspective view illustrating the pad and holder with cover and heel thereon; and Figs. 7 to 10 detail views illustrating the action of the apparatus in connection with the covering of a 35 heel.

A framing 1 is provided; this may be of any preferred design. At its head the framing 1 carries a fixed table 2 having a bracket 3 which has bearing openings 4 and 12 therein for the plunger rods 5 and 11 respectively. The table 2 also has a bearing opening 45 for the rod 5. Both rods 5 and 11 are rigidly connected to each other through the bridge piece 10 and cooperating fastening nuts 46. To the bottom of the rod 11 is adapted to be firmly secured a foot 13 by means of the pinching screw 47 or otherwise; the foot 13 has a recess 48 therein to receive an end of a heel 14 which is to be covered and such foot 13 is also suitably shaped to suit the contour of contiguous portions of the heel 14.

Table 2 has an opening 15 therein lo-

cated below the foot 13 and on the table 2 over said opening is situated a resilient pad 55 16 of rubber, leather, felt, or other suitable material and of appropriate thickness; such pad 16 is carried in a metal holder 17, and the latter with pad therein is adapted to be positioned on the table 2 through the guide 60 brackets 18 which are secured to the table 2. The pad 16 is furnished with a H-shaped slit, the connecting slit 19 joining the end parallel slits 20 and 21 respectively; the edges of the said slits are adapted to serve 65 as wiper flaps for a cover 28 when a heel 14 is being forced through the slits 19-21 in the pad 16.

Beneath the table 2 and depending therefrom are a pair of brackets 22 each of which 70 carries a trunnion pin 23 to each of which is pivoted a sector shaped wing 24. Each of the wings 24 is provided with an arm 25 to which is connected one end of the links 26 whose other end is connected to the knuckle- 75 joint bracket 6 fixed to the foot of the rod 5. Such bracket 6 has also connected thereto one end of a jawed link 7 whose other end has attached thereto an operating foot pedal 8 which is pivoted at its rear end to the frame 80 1. An extensible coil spring 9 is attached at one end to the pedal 8 and at the other end to the frame 1. Secured to the brackets 22 by screws 48 or otherwise and positioned centrally of the wings 24 is a chute 27. 85

Arms 30 may be pivoted to pins 31 fixed to the table 2; the rear end of each of the arms 30 has connected thereto one end of the respective extensible coil springs 32, the other ends of such springs being connected to the bracket 3. Each of the pins 31 is also fitted with a compressible coil spring 33; the forward end of each of the arms 30 has pivoted thereto a foot 29 (see Fig. 4), and each of such arms 30 is also provided 95 with a ramp 34 furnished with a hook 35 (see Fig. 3). A lever 36 is pivoted to the pins 31 and such lever has a pair of operating handles 37. The lever 36 is adapted to be engaged by a lever 38 which has a hook 49 and 100 is pivoted to the bracket 3, the latter having a stop 40 thereon for the lever 38. Such lever 38 is connected to one end of an extensible coil spring 30 with associated parts and lever 36 serve when in operative relation to each other to hold a heel cover 28 cen- 105

trally and in stretched position over the H-slit in the pad 16, and the lever 38 serves to sustain the lever 36 with arms 30 in upraised position while the cover 28 is being placed on the pad 16. The arms 30, lever 36, and lever 38 with appurtenant parts thereof above described may be omitted when covering material 28 which does not require to be stretched is utilized for covering heels 14 on the apparatus.

In operation, assuming that a cover 28 has been cut to suitable shape and size and has been coated on one face with an adhesive, say rubber solution, it can then be placed on the upper surface of the pad 16 over the slits 19-21 therein with its adhesive coated surface upwardly; similarly when a heel 14 has been coated with the adhesive on the portions thereof to be covered it is positioned in relation to the cover 28 with its adhesive treated portions opposite such cover. Before such positioning of the cover 28 on the pad 16, the handles 37 are elevated to enable the lever 36 to be engaged by the lever 38 whereby the lever 36 and arms 30 will be capable of elevation through operation of the lever 38 to leave the pad 16 clear to receive the cover 28. Positioning of the heel 14 in relation to the cover 28 on the pad is such that portion of the rand or heel seat 43 of the heel 14 will be located in the recess 48 of the foot 13; the breast 34 of the heel 14 will abut the lower face of the foot 13; the rand or heel 43 will be in alignment with the slit 20 of the pad 16; the face 42 of the heel 16 will be in alignment with the slit 21 of the pad 16; and the rear back 41 of the heel 14 will be in alignment with the connecting slit 19 of the pad 16. Such positioning of the cover 28 and heel 14 in relation to the pad 16 is shown in Figs. 7 and 8.

Upon release of the lever 38 from the lever 36, the arms 30 and such lever 36 descend, and the feet 29 on the arms 30 contact with the opposite sides of the cover 28, if same is to be stretched, and hold such cover in proper position on the pad 16. When the handles 37 are forced downwardly, the lever 36 cooperating with the ramps 34 on the spring controlled arms 30, such arms are forced laterally outwards and at the same time pressure is exerted on the arms 30 and feet 29 associated therewith, whereby the cover 28 is held firmly by such feet and is simultaneously stretched to prevent creasing, puckering, or bulging of the cover 28 when it is being attached to the heel 14. Subsequently the heel 14 may be positioned as beforementioned in relation to the cover 28.

After such stretching operation of the cover 28, and the said positioning of the heel 14, the pedal 8 is pressed downwardly against the action of the spring 9, and such movement of the pedal 8 enables lateral movement from each other of the wings 24 (see dotted lines, Fig. 3), the latter being associated with

the pedal 8 through the link 7 and knuckle joint 6 attached to the plunger rod 5. Movement of the pedal 8 downwardly ensures simultaneous downward movement of the plunger rods 5 and 11 whereby the foot 13 carrying the heel 14 to be covered will also be moved downwardly and the heel 14 and cover piece 28 will be forced through the H-slit of the pad 16 (see Figs. 8 and 10). In passing through such slit the cover 28 will be caused to adhere to the heel 14 through contact of the edges of the said slit with the said cover. The covered heel after passing through the H-slit in the pad 16 falls into the chute 27 through which it is delivered from the apparatus.

When pressure on the pedal 8 is released the coil spring 9 will automatically cause the pedal 8 with the plunger rods 5 and 11 and foot 13 to ascend, and when the foot 13 is clear of the pad 16 the wings 24 will operate to force the edges of the slits in the pad 16 (see Fig. 10) to normal lever position thereof (see Figs. 7 and 8). Upon raising the hand levers 37, the lever 36 and arms 30 with feet 29 (see dotted lines Fig. 2) will be upraised and may be supported in such position by the lever 38 automatically engaging with the lever 36 to enable next sequence of operations in heel covering to be effected.

What I claim as my invention and desire to secure by Letters Patent is:—

1. Method of attaching covers to heels of boots or shoes consisting in feeding an adhesively treated cover and heel and adhesive coated surfaces thereof facing one another in position onto a slitted resilient pad, and forcing the said heel and cover through the said pad, whereby the cover is made to adhere to the heel in its passage through the pad.

2. Method of attaching covers to heels of boots or shoes consisting in feeding an adhesively treated cover onto a slitted resilient pad, stretching such cover on said pad, feeding an adhesive coated heel with the adhesive coated surfaces thereof facing the adhesive coated surface of the cover onto the said cover on the slitted resilient pad, and forcing the said heel and cover through said pad whereby the cover is made to adhere to the heel in its passage through the pad.

3. Method of attaching covers to heels of boots or shoes consisting in feeding an adhesively treated cover and heel with adhesive coated surfaces thereof facing one another in position onto a slitted resilient pad, stretching such cover, and forcing such heel and cover through said pad whereby the cover is made to adhere to the heel in its passage through the pad.

4. Method of attaching covers to heels of boots or shoes consisting in cutting the material of the cover to required size and shape, treating one surface of the cut cover with adhesive, treating the heel with adhesive, feeding the cut cover with its adhesive treated

face upwardly disposed in position on a H-slitted resilient pad, placing the adhesive treated heel in position in relation to the adhesive treated cover, and finally forcing the said heel and cover through the slitted pad, whereby the cover is made to adhere to the heel in its passage through the slitted pad.

5. Method of attaching covers to heels of boots or shoes consisting in cutting the material of the cover to required size and shape, treating one surface of the cut cover with adhesive, treating the heel with adhesive, feeding the cut cover with its adhesive treated face upwardly disposed in position on a H-slitted resilient pad, stretching the cover, placing the adhesive treated heel in position in relation to the adhesive treated cover on the said pad, and finally forcing the said heel and cover through the slitted pad, whereby 20 the cover is made to adhere to the heel in its passage through the slitted pad.

6. Method of attaching covers to heels of boots or shoes consisting in cutting the material of the cover to required size and shape, 25 treating one surface of the cut cover with adhesive, treating the heel with adhesive, feeding the cut cover with its adhesive treated face upwardly disposed in position on a H-slitted resilient pad, placing the adhesive treated heel in position in relation to the adhesive treated cover on the said pad, stretching the cover, and finally forcing the said heel and cover through the slitted pad, whereby the cover is made to adhere to the heel in 30 its passage through the slitted pad.

7. Apparatus for attaching covers to heels of boots or shoes comprising a framing with an opening therein, a slitted resilient pad located over such opening, means for forcing an adhesively treated heel with associated adhesively treated cover through such slitted pad, and means for returning slitted edges of said pad to normal position thereof after a heel and cover have been passed through said 45 pad.

8. Apparatus according to claim 7, in which the framing has a table at its head in which the opening is located, a bracket on said table having bearings for a pair of

plunger rods both of which are rigidly connected to and are movable simultaneously with each other, an operative spring controlled pedal pivoted to the framing and associated with one of said rods, and a foot securable to one end of the other said rod, the 55 said foot being shaped to receive a heel to be covered and being also adapted to be located in vertical alignment with the said opening.

9. Apparatus according to claim 7, in which the framing has pivoted thereto a pair 60 of spring controlled arms, the forward ends of which respectively carry a pivoted presser and stretcher foot, a ramp on each said arm, and a lever pivoted to the framing and co-operable with said ramps when pressed downwardly to force said arms and presser and stretcher feet laterally outwards.

10. Apparatus according to claim 7, in which the framing has a table in which is an opening and the slitted resilient pad is carried in a metal holder, and guide brackets are fixed to the table about said opening to receive the said pad in its holder.

11. Apparatus according to claim 7, in which the framing has a spring controlled 75 lever pivoted thereto, the said lever being adapted to cooperate with means provided on the apparatus for holding and stretching the covering material to keep said means up-raised from the resilient pad, and a stop on 80 the framing for said lever.

12. Apparatus according to claim 7, in which the framing has depending from its head a pair of opposite brackets located between which is a delivery chute, a trunnion 85 pin in each said brackets, a sector wing pivoted to each said trunnion pins, and a link connector for each said wings to the means whereby the heel and cover are forced through the slitted resilient pad, the said 90 wings when operated in one direction being adapted to return slitted edges of said pad to normal position.

13. In an apparatus for the attachment of covers to heels of boots or shoes, a resilient 95 pad with an H-slit therein.

In testimony whereof I affix my signature.
FREDERICK BENEDICT McINTOSH.
